CLAIM

The ornamental design for a restaurant building, as shown and described.

DESCRIPTION

FIG. 1 is a front elevational view of a restaurant building showing my new design;

FIG. 2 is a left side elevational view thereof, the right side elevational view being substantially the same;

FIG. 3 is a rear elevational view thereof; and

FIG. 4 is a top plan view thereof.

FIG.1

FIG.2

FIG. 3

FIG. 4
